UNITED STATES PATENT OFFICE

156,791

COMBINED CANDY AND DOLL PACKAGE

Charles E. Whitecomb, Bayside, N. Y.

Application December 22, 1947, Serial No. 143,276

Term of patent 3½ years

(Cl. D58—12)

To all whom it may concern:

Be it known that I, Charles E. Whitcomb, a citizen of the United States, residing at Bayside, in the county of Queens and State of New York, have invented a new, original, and ornamental Design for a Combined Candy and Doll Package, of which the following is a specification, reference being had to the accompanying drawing, forming part thereof.

Fig. 1 is a top plan view of a combined candy and doll package, showing my new design.

Fig. 2 is a front elevational view thereof.

Fig. 3 is a sectional view thereof, taken on line 3—3 of Fig. 1, the contents of the box being omitted for the sake of clarity.

The dominant feature of the design resides in the portions shown in full lines.

I claim:

The ornamental design for a combined candy and doll package, substantially as shown and described.

CHARLES E. WHITCOMB.
